UNITED STATES PATENT OFFICE.

ADAM F. GOOD, OF MANCHESTER, OKLAHOMA.

OIL CAN.

Application filed April 24, 1922. Serial No. 556,345.

To all whom it may concern:

Be it known that I, ADAM F. GOOD, a citizen of the United States, residing at Manchester, in the county of Grant and State of 5 Oklahoma, have invented certain new and useful Improvements in Oil Cans, of which the following is a specification.

This invention relates to new and novel 10 improvements in oil cans and particularly to oil cans having pump means to dispense the oil.

The principal object of the invention is to provide a device of the above character that 15 consists of a container having a dispensing spout, an improved plunger for forcing oil under pressure out through said dispensing spout and improved means to be gripped by the operator to facilitate operation of the plunger.

20 A further object of the invention is to provide on oil can of the pump type that is simple in construction, strong and durable and which it is believed may be manufactured at a reasonably low cost.

25 Various other objects and advantages of my invention will become apparent during the continuance of the following description.

In the drawings:—

30 Figure 1 is a view in central longitudinal section taken through the body of my invention and

Figure 2 is a horizontal cross section taken on the line 2—2 of Figure 1.

35 In describing the invention in detail, 23 designates the container or can proper, that is equipped with a filling opening 6' normally closed through the medium of a cap 6. The can is provided adjacent its top and bottom with opposed openings 23'—23' and 40 24—24', respectively, and an opening 25 is provided in the center of the top of the can, as clearly shown.

The mechanism of the can consists of a 45 substantially U-shaped pipe arrangement 14 consisting more explicitly of an intermediate member 14' and horizontal members 12 and 26 that are positioned through the opposed openings 23'—23' and 24—24' of the can. 50 Intermediate member 14' and the members 12 and 26 are connected by T-fittings F—F' so that their communicating channels 9, 9' and 10' provide an outlet passage through which oil is adapted to pass as will be hereinafter pointed out.

The free ends of members 12 and 26 are

closed by caps 8 and 22 which may be removed, if desired, for the purpose of cleaning or for substitution of any of the working parts of the device. 60

A plunger 10 that consists preferably of a steel rod operates in the channel 9 of member 12 and projects outwardly through an opening G provided in the T-fitting F in line with the channel 9, around which opening is provided a stuffing box including an air tight packing gland 11. At its outer end the plunger 10 has a hand grip H so that it may be freely moved by the operator. Spring 10'' is positioned within the member 12 adjacent its free end and engages the inner end of the plunger to normally hold the latter in its outermost position and to yieldingly resist inward movement thereof. 70

The channel 9' in member 26 is constricted, as at 19, to form a seat 19' for a ball valve 18, the ball being normally held in a seated position through the medium of an expansion spring 18' which has one end bearing against the ball and the other end 80 engaged in a recess in the closure 15 of the T-fitting F'. Closure 15 is screwed into the T-fitting F' in line with channel 9' of member 26 and is removable so that access can be had to spring 18' and the ball valve 18. A 85 removable plug 16 is also screwed into the T-fitting F' in line with the channel 10' of member 14' so that access may be had to the passage 10' therein for the purposes of cleaning. 90

It will also be noted that member 26 is provided with a series of openings 21 within the container 23 so that the oil from the container may pass into the passage 9' thereof. 95

The T-fitting F is provided with a ring 13 having a threaded plug 13' screwed into a suitable opening in the top of the fitting and in line with channel 10'. The ring 13 serves as a finger grip for the operator when the device is used and also facilitates the 100 removal of plug 13' when the passage 10' of member 14' is being cleaned. When in operation, the operator can grasp member 14' and place one finger through ring 13 whereby his thumb will be in a position to 105 operate plunger 10.

A hollow extension 7 is provided intermediate the ends of member 12 and projects upwardly through opening 25 at the top of the container 23. The upper end of the extension is fashioned to form a valve seat and carries a coupling 3 into the upper end of 110

which is screwed the attaching plunger 2 of the spout. The ball valve 5 operates in coupling 3 and is adapted to seat on the upper end of the extension 7, a spring 4 interposed between the ball valve and the plug 2 normally holding the valve in a seated position. The tube 1 of the spout is carried by plunger 2 and has its inner end open to the interior of the coupling 3 as illustrated.

10 In operation, the plunger 10, being in its outermost position is pushed inwardly against the tension of the spring 10' and when released will be again forced to its outermost position. In moving to its outermost position plunger 10 creates a vacuum in passageway 9 in member 12 and in extension 7 which will cause the unseating of ball valve 18 in passageway 9' of member 26 thereby allowing oil from passageway 9' to pass into passageway 10' in member 14 and then fill passageway 9 of member 12. Consequently, when the plunger 10 is again pushed into member 12 the oil in passageway 9 will be forced upwardly through extension 7, unseating valve 5 and find its way out through the tube 1. It will be noted that when the plunger is pushed inwardly the valve 18 will again be seated by spring 18' thus preventing oil which is already in passageway 10' of member 14 being forced back into the can. As the inward and outward movement of the plunger continues oil will be forced outwardly through the tube 1 as is obvious.

What is claimed is:—

35 1. In a device of the character described, a container, means to facilitate the filling thereof, a substantially U-shaped structure having channels extending the length thereof and having its leg members extending 40 transversely through said container, closures for the free ends of the leg members, the lower one of said leg members being provided with a series of openings to permit 45 the flow of fluid from the container into the respective channel, a hollow extension on the other of said legs having its hollow portion

open to the respective channel and projecting through the top of said container, a check valve operating at the mouth of said extension, means for yieldably retaining said check valve in a seated position, a dispensing spout above said check valve, a check valve in the channel of the lower leg member, means for yieldably maintaining said last named check valve in a seated position, 55 and manually operated means movable in the channel of the upper leg member to open one of said check valves upon movement in one direction and the other of said check valves upon movement in the other direction 60 to force fluid through said U-shaped structure from said container to said dispensing spout, substantially as described.

2. A device of the character described, comprising a container, a substantially U-shaped hollow structure having its leg members extending transversely through said container and its intermediate portion in spaced relation to said container to provide a handle portion for the container, closures 70 for the free ends of said structure, a check valve in the lower leg member of the said structure, said lower leg member being provided with a series of openings in advance of the said check valve to permit the fluid 75 from said container to pass into the hollow portion thereof, a hollow extension on said structure projecting upwardly through the top of said container, a check valve at the upper end of said extension, a dispensing 80 spout arranged above said check valve, means to normally maintain said last named check valve in a seated position, a plunger operable in said structure between said check valves, means for yieldably maintaining said 85 plunger in its outermost position relative to said U-shaped structure and means to facilitate the filling of said container, substantially as described.

In testimony whereof I affix my signature.

ADAM F. GOOD.
